APPARATUS FOR TREATING WARP SHEETS
AND THE LIKE TO SIZE AND DRY THEM

John R. Andrews, Jr., Uxbridge, Mass., assignor
to Bachmann Uxbridge Worsted Corporation,
Uxbridge, Mass., a corporation of Massachusetts

Application November 18, 1949, Serial No. 128,134

7 Claims. (Cl. 28—28)

1

This invention relates to a method and apparatus for treating a warp sheet and the like to successively wet and dry it as for example to size and dry it, or to dye, size and dry it.

In the manufacture of cloth successive wetting and drying, and rewetting and redrying of a warp sheet is often necessary or desirable. For example fibers, especially wool, may be oily and only imperfectly sized with a single wetting, and often a warp sheet requires a first wetting with dye and a second wetting with size, and many warp sheets, such for example as cotton warp sheets, are now dyed in one operation, and sized and dried in a separate operation.

It is the purpose of this invention to provide a simple, practical and efficient method and apparatus for overcoming these deficiencies in the prior art by providing for wetting and drying and rewetting and redrying in a continuous operation and without duplication of equipment and attendant loss of mill space.

Another object of the invention is to provide a simple and efficient method and apparatus whereby warp may be repeatedly wetted with dye or size or both and dried utilizing only a single drying chamber.

Another object of the invention is to provide improved means for handling and guiding a warp sheet to dry it effectively and prevent individual threads from sticking together.

Other objects of the invention will be in part obvious or in part pointed out hereinafter.

The invention accordingly consists in the features of construction, combinations of elements, arrangements of parts, and in the several steps and relation and order of each of said steps to one or more of the others thereof, all as will be pointed out in the following description, and the scope of the application of which will be indicated in the following claims.

The invention will best be understood if the following description is read in connection with the drawing, in which the single figure is a side elevation partly in cross section illustrating the method, and preferred apparatus for carrying out the method disclosed herein.

While the method disclosed herein can be practised using a variety of types of apparatus I prefer to employ the type of drier disclosed in pending applications Serial No. 25,565, and Serial No. 122,482, the latter of which matured into Patent No. 2,601,080, and the header and air circulating means which are indicated herein are shown and described in detail in said applications and form no part of the present ap-

plication. They will be referred to herein only in a general way and as is required to explain the method and apparatus which is the subject of this invention.

5 In the figure a plurality of size baths, indicated generally by the numerals 10 and 12, are shown located adjacent to a drying closure indicated generally by the numeral 14. Instead of two separate sizing baths a single bath sufficiently long to accommodate a double set of guide rollers may of course be used.

Within drying closure 14 headers 16 and 18 are provided and disposed with their heater, fan, and duct means in such a way as to promote 15 an efficient circulation of air within closure 14. As shown herein header 16 is provided with air slots along its surface 16^a and header 18 is provided with air slots along its surfaces 18^a and 18^b. The air slots may be equipped with baffle 20 means 28 such as are shown by way of example along a portion of surface 16^a, the said baffles serving to cause the air to be ejected from the header surface with a gentle non-turbulent flow. Other baffle means may be employed if desired 25 within the headers to promote even distribution of the air along the length and width of the header discharge surfaces.

In the embodiment of the invention shown herein air enters closure 14 through the port 22 and after passing through a preheater 24 flows under and around the sides of header 18 to fan 26 by which it is impelled into header 16 and discharged through air ports or slots along the header surface 16^a in a direction substantially 30 perpendicular to the paths of a plurality of warp sheet portions extending through substantially parallel reaches in superimposed relation, as will be described. After passing through the said warp sheet portions an increment of the air is 35 drawn into fan 28 and is recirculated through duct means, indicated generally by the numeral 30, to the header 18 from which it is discharged through the air ports or slots in the surfaces 18^a and 18^b in directions substantially perpendicular 40 to reaches of the warp sheet. After leaving the surfaces 18^a and 18^b of header 18 and passing through the warp sheet the air is again drawn into fan 26 and is recirculated together with incoming air entering through said port 22. 45 Preferably an increment of the air passes through the incoming reaches of the warp sheet adjacent their entry into closure 14 and is exhausted through a discharge port indicated generally by the numeral 32.

55 In front of fan 26 there are desirably provided

the air heaters H and control means 34 for regulating the volume of air admitted to fan 26. Similarly heating means H is desirably provided within the duct 33 for reheating the air after it is discharged from header 16 and its entrance 5 into fan 28, and before it reaches header 18.

The wall of closure 14 is provided with openings 36 and 38 for the passage of three reaches of a warp sheet W, and within the closure a pair of guide rollers 40 and 42 are provided adjacent and above the narrow end of header 16, roller 42 being of smaller diameter than roller 40 and positioned in front of roller 40 and substantially in alignment between roller 40 and sizing bath 10. Beyond the narrow end of header 16 another guide roller 44 is provided and beyond the narrow end of header 18 guide roller means is shown comprising the roller 46 and rollers 48 and 50 of smaller diameter than roller 46 and positioned between roller 46 and the narrow end of header 18. A single roller of less diameter than roller 46 may be used in place of the pair of rollers 48 and 50, the latter being employed simply as a matter of convenience and to conserve space. Adjacent and below the wider end of header 18 another guide roller 52 is provided and an additional guide roller 54 is shown positioned adjacent the bottom of closure 14 and between air inlet port 22 and fan 26.

A warp sheet W is first wetted, as by passing it into a sizing bath 10. Within sizing bath 10 it passes under guide roller 56 and between a pair of rollers 58, and then is led through a long reach to and around the rollers 40 and 42 respectively, half of the warp sheet being led around each of these rollers with the result that the warp is divided into a plurality of sheets 68^a and 68^b while passing through the reach between rollers 58 and rollers 40 and 42.

After passing around rollers 40 and 42 the warp passes back through another long reach to port 36 to guide roller 62, shown herein as being located above a second size bath 12. The warp while passing through the reach between the rollers 40 and 42 and roller 62 remains divided into two halves identified by the numerals 64^a and 64^b.

After passing around guide roller 62 the warp again is in a single sheet and is rewetted in size bath 12 and after passing through the pair of rollers 66 is passed through a third reach above header surface 16^a from rollers 66 to guide roller 44. During this reach the warp sheet may be split into a number of sheets and splitter rod 28 is shown by which the warp is divided into two sheets, in combination with splitter rods 70 and 72 by which the divided warp is redivided forming four warp sheets 74^a, 74^b, 74^c, and 74^d.

After passing around guide roller 44 the warp passes through a shorter reach, entirely within closure 14, to and around the rollers 46 and 48 and 50, half of the warp passing around roller 46 and half around rollers 48 and 50, thus dividing the warp during this reach into the sheets 78^a and 76^b.

After passing around rollers 46 and 48 and 50 the warp remains divided, during a reach to guide roller 52, into sheets indicated as 78^a and 78^b. After passing around guide roller 52 the warp is led around roller 54 and out of closure 14 through port 22 against the flow of incoming air.

Thus it will be seen that above header surface 16^a three reaches of the warp are disposed in substantially parallel planes one above the other, and air discharged from said header surface 16^a will pass successively through the reach extend-

ing between rollers 66 and roller 44; the reach between rollers 40 and 42 and rollers 62; and the reach between rollers 58 and rollers 40 and 42. And it will be seen that the first reach, from rollers 58 to rollers 40 and 42 is the first reach of the warp entering closure 14; the third reach, from rollers 66 to roller 44, is the second reach of the warp entering the closure 14; and the second reach of the warp, between rollers 40 and 42 and guide roller 62, is an intermediate reach shown herein as passing out of the closure to return the warp to be resized.

It will be understood that the warp in passing through the first of the three reaches superimposed over header surface 16^a will be substantially dried before contact with rollers 40 and 42 and thus prepared for being resized upon conclusion of its travel through its second reach from rollers 40 and 42 to rollers 62; and will be again substantially dried by the time it reaches roller 44 after passing through its third reach, from rollers 66 to roller 44, this third reach being through a path closer to the header surface 16^a than said first or second reaches and therefore exposed to the drying air from the air ports or slots of header surface 16^a before the said air has contacted the portions of the warp passing through the first and second of its said reaches.

The repeated sizing of the warp as shown herein has been found to be of substantial practical value in the treatment not only of warp threads comprising oily fibers from the Bradford spinning system but also on dry fibers from the French system and the Pin Drafter system. The disposition of a plurality of reaches of the warp in superimposed relation above the single header surface has been found to give practical and efficient results while conserving space, and the dividing of the warp into a plurality of sheets 30 while travelling through one or more of its reaches has been found helpful in promoting complete and even drying of the warp, the utilization of a pair of rollers of different diameters, such as rollers 40 and 42, for this purpose having been 35 shown to be a simple and effective means for accomplishing splitting of the warp during its travel through two consecutive reaches, this means effecting desired splitting without the warp being contacted in any way between leaving rollers 58 of size bath 10 and reaching guide rollers 40 and 42. This is of substantial practical value because where splitter rollers are employed such for example as those indicated by the numerals 68, 45 70 and 72, some of the sizing is likely to be transferred from the warp threads to the splitter rollers at their points of contact thus building up 50 into accumulations on the splitter rollers which from time to time is discharged onto the warp sheet thus bridging over the space between the individual threads forming the warp sheet and causing them to be stuck together.

In the treatment of oily fibers the double dipping disclosed herein accomplishes an important result since after the first sizing and drying step the individual threads become uniformly and evenly sized in the second step.

The method and apparatus disclosed herein has the advantage that the method can be practised while continuously advancing the warp without 65 duplication or substantial increase in the size of the apparatus required.

It will thus be seen that there has been provided by this invention a method and apparatus in which the various objects hereinabove set forth together with many thoroughly practical 70 75

advantages are successfully achieved. As various possible embodiments might be made of the mechanical features of the above invention and as the art herein described might be varied in various parts, all without departing from the scope of the invention, it is to be understood that all matter hereinbefore set forth or shown in the accompanying drawing is to be interpreted as illustrative and not in a limiting sense.

What I claim is:

1. Apparatus for treating warp and the like which comprises, a drying chamber, a header having air ports along one surface positioned within said chamber, a pair of rollers positioned within the chamber and extending in parallel relation to the air ports of said header, one wall of said chamber having a plurality of openings therein, one of said rollers being larger than the other and being positioned on the far side of the other from said wall openings, means for passing a warp sheet into said chamber and around said rollers respectively and out of said chamber, through first and second reaches the second of which is disposed beneath said first reach, the part of said warp sheet passing around the smaller of said two rollers remaining separated from, and disposed between, the reaches of the part of the warp sheet passing around the larger of said two rollers, and for passing the warp sheet again into said chamber and through a third reach between said header and said first and second reaches, in a continuous operation, each of said reaches extending substantially at right angles to the air streams issuing from the air ports of said header.

2. The structure claimed in claim 1 in which means are also provided for wetting the warp sheet in advance of its first entry into said chamber and in advance of its second entry into said chamber.

3. Apparatus for treating warp and the like which comprises a closed chamber, a header therein having air ports along one surface, and means for passing a warp sheet continuously into, and out of, and again into said closed chamber, through three reaches positioned one above another and with each extending substantially at right angles to the air streams issuing from said ports of said header whereby air issuing from said air ports passes through said reaches successively in a direction substantially at right angles to said reaches, a pair of rollers for splitting the warp during its passage through said first and second reaches, one of said rollers being larger than the other and positioned on the far side of the other from the entrance and exit points of the warp into and from said chamber.

4. A dryer comprising a housing, a header therein having a number of ports for distributing air introduced into said header, said housing having a plurality of wall openings for passage of a plurality of reaches of a warp sheet, first roller means positioned outside said housing and defining the beginning of a first reach of said warp sheet, second roller means positioned within said housing adjacent the far end of the header from said openings to receive the warp sheet at the end of its first flight, third roller means positioned outside the housing adjacent and defining the end of the second and the beginning of a third reach, fourth roller means positioned within

the housing adjacent the far end of said header from said wall openings and defining the end of the third flight of said warp sheet, said third flight of the warp sheet passing nearer to the ported surface of said header than said second flight, and the said second flight of the warp sheet passing closer to the ported surface of the header than said first flight.

5. The device claimed in claim 4 including means for wetting the warp sheet prior to its passage through said first flight, and again intermediate its passage through said second and third flights.

6. A dryer comprising a housing, a header therein having a number of ports for distributing air introduced into said header, means for leading a warp through three flights above the ported surface of said header with each flight passing successively closer to said ported surface than the preceding flight, said means including port means in one housing wall for introducing a warp sheet, roller means positioned adjacent the far end of said header from said port means defining the end of said first flight and the beginning of the second flight, other roller means positioned in a plane intermediate the plane of said first flight and the plane of the ported surface of said header and defining the end of the second flight and the beginning of the third flight.

7. A dryer comprising a housing defining a first drying chamber and a second drying chamber, a passage intercommunicating between said first and second drying chambers, an air chamber intermediate said drying chambers and communicating with said first drying chamber, an air inlet port in the housing wall for admitting air into said second drying chamber, an air passageway in said second drying chamber having an intake side positioned to receive air entering said second chamber through said air inlet port and an exhaust side communicating with said air chamber, an air exhaust port in the wall of the housing for exhausting air from said first drying chamber, and means for passing a length of material through the housing wall into said first chamber and for guiding it through two reaches within said first chamber and out of the housing, and then again into said housing and through a third reach within said first drying chamber.
